FERNAND CARBENAY, OF PARIS, FRANCE.

APPARATUS FOR DEVELOPING PHOTOGRAPHIC RIBBONS.

Application filed August 28, 1921, Serial No. 496,540, and in France September 14, 1920.

The present invention relates to apparatus or machines arranged to develop photographic ribbons such as moving picture films, ribbons for continuously operating registering apparatus etc., i. e. in which the ribbon carrying the latent image is continuously fed to the apparatus and thus developed. The invention may also be used in developing the tape of photographic recorders, such as are employed in wireless and wire telegraphy.

In such continuously moving apparatus, it is necessary to vary the time during which the ribbon is submerged in the developing bath so as to obtain an image of regular intensity, notwithstanding the fact that the sensitive material may have been exposed for varying lengths of time to allow for various conditions of exposure (variations of the exposure, variations in the actinism of the light, etc.). For this purpose, a connection is established between the apparatus that feeds the ribbon into the bath and the apparatus that moves it out of the bath ordinarily at equal speed, making possible the momentary uncoupling of the two mechanisms in a manner to permit one to lag behind or advance ahead of the other. Due to this arrangement, the length of the movable ribbon, the ends of which are between these two mechanisms, will vary. Generally stated, this connection is established under the control of two mechanisms, by means of a single driving shaft with which both mechanisms are connected through the agency of more or less rapidly and readily operable gears. In most of the apparatus of this type, the regulation of the time during which the ribbon is submerged in the developing fluid is accomplished at the beginning of each operation, and cannot be modified during the operation of the apparatus.

In accordance with the present invention, means are provided for making possible the continuous and ready variation of the time during which the movable ribbon is submerged in the developing bath, and to accomplish this while the machine is in operation. Due to this arrangement, the operator may retard or accelerate the passage of the ribbon, depending on the showing of the picture developed.

The invention may be carried into practice in a variety of ways. The accompanying drawings illustrate embodiments of the in-

vention for the purpose of exemplifying it and not limiting its scope, and to facilitate the understanding of the system.

Fig. 1 is a view in plan and partly in section of developing apparatus embodying the invention;

Fig. 2 is a view of the developing apparatus in front elevation;

Figs. 3 and 4 are plan views of developing apparatus comprising different forms of the invention;

Fig. 5 is a detail view of the clutch controlling mechanism employed in the form of the invention shown in Fig. 4.

The ribbon 1 (Fig. 1) is moved into each of the developing baths 2 under the control of a feeding roll 3. The ribbon is moved out of the bath in a similar manner under the control of a take-up roll 4. The roll 3 is operated by means of motor mechanism in any well-known manner, e. g. through the agency of a belt 5' and the pulley 5. The same mechanism operates the take-up roll 4 through the agency of the pulleys 6 and 7, 70 and belt 7'.

In accordance with the present invention, a differential arrangement may be introduced, for example, between the pulley 7 that receives the driving power and the take-up roll 4 in the following manner:

A casing 8 carries two bevel gears 9 and 9', called satellites. These gears intermesh on one hand with the primary bevel-gear 10 fastened to the pulley 7, and on the other hand, with the secondary bevel-gear 11 which is adapted to rotate the take-up roll 4. The differential casing may be rotated around the principal shaft at the will of the operator, e. g. by means of a toothed rim 12 90 operated by a gear-wheel 13 attached to the handle 14, or in any other similar manner. It will be seen, therefore, that when the handle remains stationary, the take-up roll 4 is operated at the same speed as the feeding roll 3, 100 whereby the length of ribbon between the two rolls remains invariably the same. When the handle is moved in one direction or the other, the speed of roll 3 will be different from that of roll 4, whereby the 105 length of ribbon between the two rolls will be increased or decreased.

Notwithstanding the fact that the arrangement of Fig. 1 may be adapted to control both the feeding and the take-up rolls 110 of the machine, its general use will be restricted to the take up rolls arranged to re-

move the ribbon from the developer. The further improvements of Figs. 3 and 4 provide a more simple driving arrangement for the ribbon holding rolls. These improvements also contemplate the provision of a differential arrangement between the driven roll and the one that precedes it. In accordance with the improvements, the difference in the movements of the two rolls is not varied during the operation, but is determined prior to the operation and is effected upon the starting of the machine.

The mechanism in accordance with the improvements is arranged in the following manner: Means are provided for retarding the coupling between the controlling shaft and the driving shaft. The driving power may be transmitted either through a single shaft driving all the rolls, or by successively controlling a roll by the said shaft through the agency of an intermediate driving shaft.

Fig. 3 represents one exemplification of this feature, intermediate shafts being used. In this figure, 21 represents the feeding roll, 25 its shaft, 23 a coupling which is preferably elastic (cylindrical or conical gears, chains, etc.), 24 is a shaft controlling the feeding roll through the agency of clutch 23. In the drawing, this shaft is represented as an extension of the shaft of the roll, but such arrangement is not obligatory and may be varied depending on the type of coupling 23 that is adopted. The shaft 24 is suitably supported on the cross beams 25 and 26 which are rigid with the frame of the machine. A toothed wheel 27 is freely rotatable on the shaft 24, and carries a clutch member 28. This same shaft carries also a traveling clutch member 29 cooperating with 40 28 and adapted to slide in a longitudinal direction. In response to the rotation of this clutch member 29, the shaft 24 is also rotated, the connection between the two being provided in any well-known manner (a 45 square section of the shaft in the path of the traveling cog-wheel, a long key, etc.) The translating movement of the traveling clutch member is effected by means of an arm 30, one end of which forms a support 31 for 50 the clutch member, and the other end 32 having the form of a screw-threaded half-cylinder engaging screw threads 33 on the shaft 35 through the agency of which the movement is transmitted from the driving 55 mechanism to the gear 27. This shaft is supported in the cross-beams 25 and 26 and is driven by any suitable means connecting it with the motor mechanism. A ratchet wheel 36 and a chain 37 being shown for this 60 purpose. The shaft 35 transmits its movement to the freely rotating toothed wheel 27 through the agency of the toothed wheel 38 rigidly connected with the shaft. This ensemble constitutes the mechanism I by 65 means of which the ribbon feeding roll 21

is operated. The next feeding roll 41 is driven by means of mechanism II which is like mechanism I and is driven by the latter through the agency of the toothed wheels 39 and 56. The wheel 39 is rigidly attached to the shaft 24 and the wheel 56 is rigidly attached to the intermediate driving shaft 55 of the mechanism II. In this manner, all the constituting feeding rolls 21, 41, 61, 81, etc. of the machine may be successively set in operation. The starting and the operation of the machine may now be easily understood. The end of the photographic ribbon to be developed is successively engaged by the rolls 21, 41, 61, 81, etc. 70 Depending on the length of the ribbon that one desires to submerge in the bath ahead of each roll, the half nuts 32, 52, 72, etc. are placed at a greater or lesser distance on the corresponding screws 33, 53, 73, etc., and the motor mechanism is started. The shaft 35 rotates and causes the traveling of arm 30 and the cog-wheel 29. At the end of its travel, the cog-wheel 29 engages the toothed wheel 27 which is rotating under the control of the toothed wheel 38. The shaft 24 is now rotated and rotates in turn the feeding roll 21. The ribbon is submerged in the bath by means of some kind of tensioning device, and the length of the submerged portions increases until the feeding roll 41 is started. The time when this occurs, depends on the position of the half nut 52 on the screw 53.

Fig. 4 represents another embodiment of the invention. In accordance with this arrangement, the motive power is transmitted directly to each feeding roll through the agency of a single transverse shaft. In this figure, 21 represents the feeding roll to be controlled, 102 its shaft, 103 an elastic coupling, 104 a driving shaft supported in the cross-beams 25 and 26, as explained in connection with the previously described embodiment of the invention (Fig. 3). The shaft 104 is set in motion by means of a wheel 107 having spirally arranged teeth and attached to the shaft. This wheel is driven by means of a wheel 108 located below the former and provided with spirally arranged teeth. The vertical plane of wheel 108 is at right angles to the vertical plane of wheel 107. By means of any suitable arrangement (such as the one to be hereinafter set forth), the wheel 108 may be rigidly mounted on the main transmission shaft 109. In this manner, the transverse shaft 109 will drive the roll 21. The driving of the succeeding roll 41 is accomplished by similar means under the control of the same shaft. In accordance with the specific embodiment of the invention herein described, the automatic coupling of the shaft 124 to the main transmission shaft is effected in the following manner: The shaft 104 has a screw 125

threaded portion 110 with which a half nut 111 is maintained in engagement by means of any suitable elastic device. An arm 112 connects the half nut with a sleeve 113 slidably mounted on a guide 114. By overcoming the tension that maintains the half nut 111 in engagement with the screw threads, the device 111, 112, 113 may be rotated around (or with) the guide 114 and by longitudinally displacing it, the nut 111 may be placed on any part of the screw threaded portion 110. This portion of the arrangement is similar to the one described in connection with Fig. 3 and numbered 30, 31 and 32. A sleeve 113 is provided with an extending finger 114' adapted to engage the elbow 115. The wheel 128 provided with spirally arranged teeth is freely mounted on shaft 109 and carries a clutch member 140. The clutch member 140 is arranged to engage the cooperating clutch member 116 that is mounted on the shaft 109 and is rotatable therewith. Under the control of a spring 117, these clutch members are normally in engagement with each other. The two clutch members may be separated by means of a lever 118 arranged to push back the member 116. The lever 118 is freed in response to the engagement of the elbow 115 by the finger 114', whereupon the roll 41 is set in motion. It will be seen therefore, that counting from the time when the preceding roll is started, the starting of the next roll depends on the positioning of half nut 111 on the rack 110. By means of this arrangement the length of ribbon to be submerged between two feeding rolls may be predetermined. If it is desired to modify this length during the operation of the machine, the following operations must be performed: To lengthen it; the lower feeding roll must be held stationary by actuating the associated lever 118. To shorten it; the lower roll is uncoupled, and by means of a handle 139 attached to the shaft of the roll (or operating this shaft through the agency of a speed-up gearing) the roll is rotated at a greater speed than the preceding roll. Each roll might be provided with a set of mechanism like the one described in connection with feeding rolls 21 and 41. These sets of mechanisms constitute the ensembles I, II, III, etc.

The troughs that form a part of the developing machine, and particularly the trough or troughs containing the developing fluid, have a relatively long tubular

shape, and are connected by means of two holes, one in the lower and the other in the upper part of the trough, with the tank containing the bath. By means of thermosiphon arrangement the liquid may be kept in circulation. In the winter, the liquid is heated by means of an electrical resistance traversed by a current of variable strength, 60 and in the summer, the liquid is cooled by passing it through a refrigerator. The average temperature may be determined by means of a thermometer suitably located with respect to the troughs. Obviously, if 70 the capacity of the trough is sufficient, the tank may be eliminated and the thermosiphon tubing connected only with the temperature controlling devices.

It will clearly appear to those skilled in the art that, the construction may be modified in various ways without departing from the spirit of the invention. The above described arrangements are merely for the purpose of exemplifying the invention and not 80 for limiting the scope thereof.

Having described my invention, what I claim is:

1. In apparatus for developing photographic ribbons, a developing tank, feeding rolls, a common driving means for all of said rolls, means for coupling each of rolls to the driving means, and means for effecting the coupling between the driving means and certain of the rolls at different times. 90

2. In apparatus for developing photographic ribbons, a developing tank, feeding rolls, means for driving the rolls including a drive shaft, a shaft for each roll and sets of coupling members for the rolls, each of 95 said sets comprising members operatively connected to the drive shaft, and one of the roll shafts respectively, and controlling means for placing said coupling members into engagement at predetermined intervals. 100

3. In apparatus for developing photographic ribbons, a developing tank, feeding rolls, each fastened on a separate shaft, a driving shaft, a plurality of gears on the driving shaft, each of said roll shafts having 105 a gear cooperating with one of said driving gears, coupling means on said drive shaft for coupling the driving gears to the roll shafts and means operated by the roll shaft of a preceding roll for operating the coupling means of a subsequent roll after a predetermined movement of said preceding roll. 110

FERNAND CARBENAY.
